REMOVABLE THREAD FOR OIL SAVERS

Filed Aug. 23, 1926

INVENTOR
JAMES NEIL LOCKE
BY

K. L. Dreckman
ATTORNEY.

UNITED STATES PATENT OFFICE

JAMES NEIL LOCKE, OF LONG BEACH, CALIFORNIA

REMOVABLE THREAD FOR OIL SAVERS

Application filed August 23, 1926. Serial No. 131,087.

Oil savers heretofore in use had a very serious defect, namely, the tendency of the swab or drilling tool to strike the head without warning—often the case when a large gas pocket is encountered, or where there has been miscalculation as to the position of the tool in the casing. This striking of the tool against the head resulted in breaking either or both the tool, or head, or the cable would part, allowing the tool to fall into the well with disastrous effects.

The object of my invention is to provide a simple and inexpensive means of overcoming the defects previously described.

15 A further object is to provide replaceable and removable threads for oil saving head, which may be quickly inserted, and the head replaced if the tool should strike said head and shear off the heads.

20 Other objects, advantages and features of my invention may appear from the accompanying drawing, the subjoined detailed description, the appended claims, or in the operation and use of my device.

25 In the drawing:

Fig. 1 is a side elevation of my oil saver with the removable threads mounted thereon.

Fig. 2 is a side elevation of half of the oil saver and attached threads, and with the cap 30 shown in section.

Fig. 3 is a perspective view of one half of the removable threads.

Fig. 4 is a perspective view of a fragment of the oil saver and with half of the removable threads in position.

Referring more particularly to the drawing: My oil saver head *a* is formed in two complementary halves 1 and 2. A central bore 3 is provided in my oil saver, through 40 which the cable operating the drilling or swabbing tool extends. Suitable packing rings 4 are positioned in the head *a*, about the bore 3, to prevent leakage of oil past the cable operating in said bore. A gland 5 formed in halves, bears against the top of the packing 4 and is held in position by a head 6 threaded on the upper end of the head *a*.

50 My oil saver is mounted in the top of the casing or flow tubing by the threads 7 which

screw into the same. These threads are formed on complementary half shells 8 and 9, which are removably mounted on the lower end of the sections 1—2, respectively. The sections 1—2 are each provided with a groove 10 and a slot 11, into which a ring 12 and strip 13 on the cups 8—9 are adapted to fit. Thus it will be seen that the threaded shells are securely and non-rotatably mounted on the head *a*. The groove 10 and ring 12 are so accurately formed that the threads on the shells 8—9 will coincide. A bottom 14 is formed on each of the shells 8—9 against which the bottom of the head *a* bears, thus further accurately positioning the said shells.

I prefer to form the shells 8—9 of a soft metal or alloy such as babbitt, zinc alloy, etc., so that when the tool strikes the head the threads on the ring 12 will shear off, permitting the tool to carry the head upwardly without injury thereto. The sheared shells 8—9 may now be quickly and easily replaced with a new set and the head *a* again set in position.

Having described my invention, I claim:

1. In an oil saver head having a transverse groove and longitudinal slots therein, externally threaded complementary shells, a rib on said shells adapted to fit into said groove, strips on said shells adapted to fit into said slots, thereby removably and non-rotatably mounting the shells on the head.

2. In an oil saver head having a transverse groove and longitudinal slots therein, externally threaded complementary shells, a rib on each of said shells adapted to fit into said groove, strips on said shells adapted to fit into said slots, thereby removably and non-rotatably mounting the shells on the head, said shells being formed of a softer metal than the head so that the threads on said shells will shear off without injuring the head.

In testimony whereof, I affix my signature.
JAMES NEIL LOCKE.
